CLAIM

USPC D7/507, 509, 510, 511, 512, 513, 523, D7/529, 532, 608, 391, 392.1, 300.2, D7/619.1, 514, 396.2, 605, 515, 517, 520, D7/342, 675; 220/669, 737, 673, 675, 715; 229/402; 206/520; D9/745, 500, 502, D9/562, 629, 516, 449, 436, 440, 504; D3/202; D11/143, 144, 153

The ornamental design for a beverage carbonation system bottle, as shown and described.

CPC A47G 19/22; A47G 19/2216; A47G 2019/2277; A47G 19/2272; A45F 3/20; A45F 2003/205; B65D 3/06

DESCRIPTION

See application file for complete search history.

FIG. 1 is a top perspective view of a beverage carbonation system bottle in its closed position showing my new design; FIG. 2 is a bottom perspective view thereof;

FIG. 3 is a front elevational view thereof;

FIG. 4 is a top plan view thereof;

FIG. 5 is a bottom plan view thereof;

FIG. 6 is an exploded top perspective view of a beverage carbonation system bottle in its open position;

FIG. 7 is an exploded bottom perspective view thereof; and,

FIG. 8 is an exploded front elevational view thereof.
